Primary Examiner — T Chase Nelson*Assistant Examiner* — Jonathan J. Han(74) *Attorney, Agent, or Firm* — McInnes & McLane, LLP; Jodi-Ann McLane(57) **CLAIM**

The ornamental design for a flat key ring, as shown and described.

DESCRIPTION

FIG. 1 is a top plan view of an embodiment of a flat key ring; FIG. 2 is a front top perspective view thereof;

FIG. 3 is a front elevation view thereof;

FIG. 4 is a rear elevation view thereof;

FIG. 5 is a right-side elevation view thereof; and,

FIG. 6 is a left-side elevation view thereof.

The broken lines shown in the drawings depict portions of the flat key ring that form no part of the claimed design.
